TELEGRAPH TRANSMITTER

Louis M. Potts, Evanston, Ill., assignor to Teletype Corporation, Chicago, Ill., a corporation of Delaware

Application September 26, 1936, Serial No. 102,771
Renewed October 18, 1939

21 Claims. (Cl. 178—17)

The present invention relates to telegraph signaling apparatus and more particularly to transmitters for issuing telegraph signals identified with printing telegraph systems.

Among methods of telegraph communication, two systems of telegraph transmission in general usage are known as permutation or Baudot code and step-by-step code. The former system of transmission utilizes an equal length time interval as a signal unit during which a definite number of sub-intervals are identified with predetermined electrical signal conditions in accordance with a permuted code consisting of five or six of said sub-intervals or signal elements. Both systems of transmission are used extensively and independently of each other but for some purposes of signal communication it is deemed desirable to be able to employ permutation code signals for trunk line or general dissemination and step-by-step signals for local communication and printing operation.

Accordingly, an object of the present invention is to provide simple, inexpensive, and reliable apparatus for converting permutation code signals into so-called step-by-step signals.

Another object of the present invention is the provision of apparatus for converting permutation code signals manifest by transverse perforations in the control form into groups of step-by-step line variations.

In contemplating the foregoing objects there are taught in the following disclosure, two fundamental embodiments of construction, one utilizing electromagnets in the translation from one code to the other, while a second embodiment utilizes an all-mechanical apparatus for accomplishing the same purpose. A pin barrel selector mechanism is provided with a coded series of discs, the periphery of which is notched. A plurality of selectable pins distributed about the discs are individually selectable to respond by a shifting motion. With each change of code signals, a previously conditioned selector pin is cammed out as its successor is selectively actuated. A shaft concentric of the selector mechanism carries a seeker arm which is frictionally driven and which is arrested upon its encountering a selected pin. The restoration of each pin to its normal or unactuated position releases the seeker arm which thereupon rotates until it encounters a subsequently selected pin, describing a predetermined angle of rotation and permitting the concentric shaft to rotate accordingly through a measured angular distance. A line interrupter also carried by the shaft causes to be generated a succession of current variations which, by their number, indicate the angular rotation of the transmitter shaft. A step-by-step printing mechanism designed in accordance with the signal transmitter shaft consummates a printing

shaft rotation under the control of the step-by-step signals thus communicated.

For a more comprehensive understanding of the present invention, attention is directed to the detailed specification following hereinafter and to the illustrations in the accompanying drawings, in which

Fig. 1 is an end elevation of a translator mechanism having portions broken away and embodying the principles of the present invention;

Fig. 2 is a longitudinal sectional view of the apparatus disclosed in Fig. 1 and is taken approximately on line 2—2 thereof;

Fig. 3 is a circuit diagram illustrating the electrical connections of the apparatus featured in Figs. 1 and 2;

Fig. 4 is an end elevation with parts broken away of a modified apparatus featuring an all-mechanical translator unit; and

Fig. 5 is a longitudinal sectional view taken approximately on line 5—5 of Fig. 4.

Referring now particularly to Figs. 1, 2, and 3, the reference character 11 indicates a supporting wall or fixture upon which there is mounted a stationary sleeve 12 having spacer flanges 13, one of which abuts the supporting wall 11 and the other an endmost plate 14. Concentrically of the stationary sleeve 12 there passes a transmitter shaft 15 journalled in the bearings 16 and tending to be driven by a pinion 17 which is supported between the felt slip washers 18—18 of a clutch assembly 19. The driven pinion 17 is connected in driving relationship with a worm 21 which in turn is secured to a power shaft 22 which revolves at the reception rate of a step-by-step printer or any other step-by-step receiving mechanism.

The rotation of shaft 15 is permitted until a stop arm 23, carried at its right end, Fig. 2, collides with the extremity of a selected one of a plurality of selector pins 24 circumferentially arranged about the sleeve 12 and supported at one end within the already mentioned end plate 14 which is suitably notched to receive said pins 24, at an intermediate point within a plate 25 which is similarly notched but whose notches 26 are cut deeper than are those of plate 14, and at their other ends by an end plate 27 whose notches 28 are deep cut and more nearly like those of plate 25. The pins 24 are shaped to afford a pair of ripples as at 29 about which there are held in position a pair of garter springs 31. A tie-in spring 32 resembling the garter springs 31 fits about the outwardly turned end portions 33 of pins 24, as indicated in Fig. 2, maintaining them against longitudinal displacement as the garter springs 31 urge the several pins 24 inwardly.

Near their right ends selector pins 24 are pro-

vided with friction reducing rollers 34 which align with and engage the periphery of associated selecting discs 35, see also Fig. 1. The discs 35 are freely rotatable upon sleeve 12 and are designed in accordance with a plan so that each disc is peculiarly notched to afford various V-shaped projections and complementary intervening notches. The distribution of the projections and the notches of discs 35 is such that for each angular disposition of the several of them there may be afforded a transverse alignment of notches beneath the rollers 34 of one of the selector pins 24, permitting said selector pin 24 to drop into a position such as that indicated by the posterior pin seen in the upper portion of Fig. 2. When in this position, the extremity of a selector pin 24 lies in the path of the end of stop arm 23.

Selecting discs 35 are each shifted through but a slight angular distance, and for regulating this movement each disc is controlled by a rock shaft 36 which is journaled at 37 in the end plate 27 and at 38 in the end plate 14. Each rock shaft 36 passes through the openings 39 of the several of said selecting discs 35 but aligning opposite one of said discs within its opening 39 an arm 41 secured to shaft 36 is articulated by a disc and slot connection, as indicated 42 in Fig. 1. An arm 43 secured to each rock shaft 36 serves as an armature under mutual control of a pair of magnets 44 and 45, so that upon the energization of a magnet 44, an armature 43 and its associated rock shaft 36 is rocked counterclockwise (Fig. 1), causing through arm 41 a particular one of the selecting discs 35 to be similarly shifted, while upon the energization of the other of each pair of magnets 45, selecting disc 35 is rotated clockwise. Each selecting disc 35 is in this manner under the control of a pair of magnets 44-45, see also Fig. 3. The energizing circuits for the magnets 44 are traceable in Fig. 3 from ground through battery 46, conductor 47, the winding of each of the magnets 44, thence over individual conductors 48-1 to 48-5 to the lower contact points 49 of the levers 54 of the tape sensing unit generally indicated 51, the contactors of any levers 54 in its counterclockwise position, common conductor 91, contact pair 68-75, to ground. The circuits of magnets 45 are traceable in the same manner from ground and battery at 46, through the conductor 47, winding of magnets 45, thence over individual conductors 52-1 to 52-5 to the upper contact points 53 of the feeler levers 54 of the tape sensing unit 51, the contactors of any lever 54 in its clockwise position, common conductor 91, contact pair 68-75, to ground. When a feeler lever 54 is presented in its counterclockwise position, which is its response pursuant to encountering a perforation in a tape perforated in accordance with a permutation code, its grounded contactor is disposed to communicate with the so-called marking contact 49, causing to be energized a magnet 44, but when a feeler lever encounters an unperforated position in the tape, it is caused to be disposed in its clockwise position whereat its contactor engages its so-called spacing contact 53, causing to be energized, instead, a magnet 45.

As has already been said, the energization of the magnet 45 results in the shifting of a particular selecting disc 35 clockwise or into its spacing position, while the energization of the magnet 44 causes its associated selecting disc 35 to be shifted to its counterclockwise or marking position. As each set of perforations (five in the

instant case) is sensed by the feeler levers 54, the five selecting discs 35 are correspondingly positioned, causing to be selected a particular one of the selector pins 24 and concurrently camming out the preceding selected one of the pins 24. This causes stop arm 23 and shaft 15 to be released from one angular position and to rotate until arm 23 encounters another pin 24, describing as it does so, a measured or predetermined angle of rotation.

Stop arm 23 carries a pair of pivot pins 55 and 56 upon the former of which there is supported a lever 57, the outer end of which is formed with a skid portion 58. As stop arm 23 is rotated in passing from one selected position to another, an oncoming selector pin 24 is encountered by the skid lever 57 which thereupon rocks clockwise as viewed in Fig. 2, about its pivot 55. This motion on the part of lever 57 communicates a counterclockwise movement to a lever 59 which is pivoted on pin 56. The innermost end of lever 59 terminates as at 61 with a ball which is disposed in line with the axis of transmitter shaft 15 and which at all times engages one blade 62 of a pair of contactors 62-63, closing an energizing circuit which supervises the advancing of the perforated tape. This circuit is traceable on Fig. 3 from grounded battery at 64, through the contact pair 62-63, conductor 65, and part of the winding of an intermediate relay 66.

As a result of the energization of relay 66, its armatures 67 and 68 are attracted to their front contacts 69 and 71 respectively. Armature 67 completes a locking circuit which is traceable from grounded battery at 72, through the contact pair 73 (which is normally closed), line 74, contact pair 67-69, and part of the winding of relay 66 to ground. Relay 66 is thus maintained energized after the skid 58 has passed over a selected pin 24 and has returned to its normal position, as viewed in Fig. 1. As a result of the movement of contactor 68 from its back contact 75 to its front contact 71, there is prepared a circuit which is traceable from grounded battery at 76, through the winding of a slow-to-operate relay 77, conductor 78, and contact pair 68-71 to ground. Since relay 77 is slow to operate, there lapses an interval before the completion of a circuit which is traceable from grounded battery at 79, through the winding of a solenoid 81 which returns the feeler levers 54, conductor 82, and contact pair 83 to ground. The closure of contact pair 83 is the result of the operation of slow relay 77 and results in the actuation of solenoid 81, which moves its plunger 84 leftwardly, Fig. 3, causing a counterclockwise rotation of the return bail 85 which rocks the several feeler levers 54 clockwise and which also closes a circuit traceable from grounded battery at 86, through the winding of release relay 87, conductor 88, and contact pair 89 which is closed as a result of the movement of bail 85 to ground. As a result of the delay introduced by the operation of relay 77 there is effected a prolonged signal or marking condition over the line 93. This signal operates at the remote station to energize a slow-to-operate relay, which results in producing a print operation in a manner well known in the present art. The construction of sensing unit 51 and the manner in which solenoid 81 operates to withdraw the feeler levers cyclically is not fundamental to the present invention but for a comprehensive understanding of such a record reader arrangement, reference may be had to a publication entitled "Tape Duplex System Bulletin No.

101" published by the Morkrum Company and copyrighted in 1918, wherein Fig. 14 illustrates an arrangement of feeler levers which may be employed in a system such as is here featured in Fig. 3.

As a result of the energization of release relay 81, the contact pair 73 is opened, breaking the aforescribed locking circuit for relay 66 and permitting the release of armatures 67 and 68 of relay 66. Armature 68, in closing its back contact 75, reestablishes ground to conductor 91 which communicates as at 92 with each of the feeler levers 54 and their contactors. As a result, several circuits, 48 or 52, are simultaneously prepared, causing to be energized the magnets 44 and/or 45 in accordance with a newly presented code signal.

In response to the aforescribed supervision of transmitter shaft 15, there is imparted to it angular rotation of varying degrees, depending of course in each case upon the angular distance between a previously arrested position and a succeeding one. Step-by-step line signals are issued over a line 93, Fig. 3, when an interrupter cam 94, secured to shaft 15 and having a plurality of cam projections on its periphery, engages and actuates the reciprocating contact spring 95 between its negative supply contact 96 and its positive supply contact 91. These current pulsations impressed on line 93 may then be used in the control or energization of a conventional pallet escapement or contactors of a step-by-step printing mechanism such as the step-by-step stock ticker. In lieu of positive and negative pulsations, current and no-current signals may be employed as is well known in the art of printing telegraphy. In accordance with well-known telegraph printing devices, the prolonged or continuous signal which follows a series of said pulsations or current variations is employed to energize a slow-to-operate relay which thereupon consummates a printing function by releasing a print hammer or by executing a type printing operation.

Modifications

In Fig. 4, a tape sensing device is indicated generally 101. Here too there are employed a plurality of tape feeler levers 102 pivoted at 103 and reciprocated between a clockwise extreme position as illustrated in Fig. 4 and a counter-clockwise position which is influenced by individual springs 104 during which the feeler pins 105 protrude through the table 106 and the control tape, and during which the limiting bar 107 will touch the opposite surface of the oversized aperture 108. In accordance with the position of the several feeler levers 102, their transfer projections 109 and 111 are correspondingly placed so as to communicate a symmetrically opposite movement to an associated one of a plurality of transfer levers 112 whose articulation discs 113 are fitted into recesses 114 of a set of selecting discs 115 which correspond to the selecting discs 35 aforescribed. In the embodiment under discussion, the selector pins 116 are grouped to occupy but one-half of the peripheral space surrounding the barrel assembly while the stop arm lever 117 is of a duplex nature having a system of levers 118 and 119 at each end. The setting of the feeler levers is communicated to the selecting discs 115 by the transfer levers 112 as aforesaid when the supporting bail 121 which carries the several transfer levers 112 is rocked to and fro by the bell crank 122 which is pivoted 75

at 123 and whose follower roller 124 is actuated by a quadruple cam 125. The shaft 126 carries an assembly sleeve 127 upon which is integrally formed not only the aforementioned cam 125 but also a tape feeler and feed cam 128 and a stop disc 129. Assembly sleeve 127 is frictionally carried upon a journal bearing 131 between slip washers 132 under tension of a clutch spring 133. Motion is imparted to shaft 126 from a prime operating shaft 134 whose worm 135 drives not only the gear 136 of shaft 126 but also a gear 137 which is frictionally carried upon the distributor shaft 138. Thus while shaft 126 is rotated continuously and its driven sleeve 127 is periodically released for rotation, gear 137 is driven continuously and the entire distributor shaft 138 is released for rotation only periodically.

Driven gear 137 is supported between a pair of slip washers 139 in a clutch assembly 141. Shaft 138 is journaled at 142—142 in frictionless bearings and carries at its remote end the aforesaid duplex lever 117 whose arms 118 and 119 function in a manner quite similar to the aforescribed levers 57 and 59. That is to say, as a particular lever system is passing through the vicinity of the selector pins 116, a skid 143 integrally formed with the levers 118 encounters and is rocked by a selected one of the selector pins 116, the latter being conditioned by the discs 115 in the same manner as described in the preferred embodiment. In this construction, however, the movement of the intermediate levers 119 causes to be imparted a corresponding movement to a clutch release lever 144 which is pivoted at 145 and which is articulated as at 146, Fig. 5, to a bell crank 147 pivoted at 148, which actually stops the assembly sleeve 127 by its intervention before one of the teeth of stop disc 129. Thus, while the communication of a particular code signal to the discs 115 causes shaft 138 to be released, assembly sleeve 127 is not released until the newly selected selector pin 116 has been encountered by stop arm 117 whereupon the apparatus is in readiness to receive a new signal for which assembly sleeve 127 is freed to execute its tape advancing, feeler withdrawal, and rearresting functions. It will be noted that the cam and disc assembly carried by sleeve 127 is designed to afford quadruple actuating elements. That is to say, the assembly need consummate but one-fourth revolution in order to actuate the tape feed lever 154 and through its bail 155 the several feeler levers 102, while the bell crank 122 is effecting the transfer operation.

In the modified apparatus featured in Figs. 4 and 5, the selecting discs 115 are coded throughout but one-half of their periphery as may be noted from the distribution of the selector pins 116. This arrangement permits of certain conveniences in assembly, but in order to constitute each half revolution of distributor shaft 138 subservient to signal propagation, there is provided the aforementioned duplex lever 117, each arm of which is effective for a half cycle of revolution, while its opposite arm is idle. As in the case of the preferred embodiment, the selector pins 116 are retained and influenced inwardly by a garter spring 149 and a tie-in spring 151. Also as in the preferred embodiment, an interrupter cam 152 is secured to distributor shaft 138, causing to be alternately made and broken the contact pair 153, which generates current pulsations in a signaling line.

In this embodiment, it is to be noted that the

condition of the perforated tape is communicated to the selecting discs 115 by mechanical devices. In accordance with the transverse perforations in the tape, feeler levers 102 being influenced by their individual springs 104 assume corresponding positions, presenting their transfer projections 109 or 111 correspondingly opposite their associated transfer levers 112. The movement of feeler levers 102 withdrawing and presenting them concurrently to the tape is controlled by shaft 126 acting through cam 128 and tape feed lever 154. Immediately following the tape feed and feeler lever withdrawal operation, cam 125 rocks bell crank 122, causing the discs 115 to be shifted and to assume positions corresponding to those of the feeler levers 102. As a result, a particular selector pin 116 is cammed out of selected position and another one received into selected position. This frees lever 117, permitting it to rotate throughout a portion of a revolution until it encounters the newly selected pin 116 whereat it is again arrested. As a skid 143 approaches the foremost portion of a newly selected pin 116, it is rocked about its pivot, giving motion to the innermost lever 119 and causing the stop bell crank 147 to be withdrawn momentarily from stop disc 129, which permits shaft 126 to be initiated into another quarter revolution, for bell crank 147 is immediately restored to its normal position as skid 143 and its train of levers glide over the selected pin 116 and are permitted to resume their normal position.

Meanwhile, shaft 138 has been permitted to describe a predetermined degree of rotation corresponding to the angular distance between its previously arrested position and its current one. This angular rotation is manifest by a corresponding number of line pulsations which are generated by the cam 152 and the contact pair 153.

While the present invention has been explained and described in accordance with specifically illustrated embodiments, it will be noted that numerous modifications may be invoked without departing from the spirit of the present invention, as defined by the hereinafter appended claims.

What is claimed is:

1. A telegraph transmitter comprising a rotary member, a plurality of actuators for conditioning said member, a line switch actuatable in accordance with the angular rotation of said rotary member, a stop means associated with said rotary member and controlled by said actuators for determining the angular rotation thereof, said plurality of actuators individually conditioned to block said stop means, a set of selecting discs for conditioning said plurality of actuators, a tape sensing mechanism for positioning said discs in accordance with the control markings of a tape including means for advancing said tape intermittently, and apparatus for initiating said tape advancing means under the control of said rotary member.

2. A telegraph transmitter comprising a selector mechanism, a rotary member controlled in its travel by said selector mechanism, a transmitter including a line switch actuatable in accordance with the rotation of said rotary member, a controlling skid lever supervised by said rotary member, a tape sensing mechanism, and means associated with said skid lever for initiating said tape sensing mechanism in response to predetermined operation of said rotary member.

3. In combination, a transmitter mechanism actuating shaft and a tape sensing mechanism actuating shaft, a pulsator carried by said transmitter actuating shaft for generating line variations to control step-by-step printing mechanism, a stop arm carried by said transmitter actuating shaft having an extremity which traverses a path, a plurality of individually selectable elements disposed in alignment bordering said path, a set of permutation code discs for individually conditioning each element to be moved into said path of said stop member, a set of permutation code tape sensing levers, means for cyclically withdrawing said levers, a control tape feeding apparatus cyclically actuated by said sensing mechanism shaft, and means under the control of said stop arm for releasing said sensing mechanism shaft periodically.
  4. In a telegraph transmitting mechanism, a record reader comprising a set of tape sensing elements and a tape advancing member, a set of coded selectors, means to communicate a permutation code setting from said tape sensing elements to said set of coded selectors cyclically, a plurality of selectable members individually conditioned by said selectors, an apparatus traversing the proximity of said plurality of selectable members and arrestable by a conditioned member, said apparatus including means for initiating the operation of said tape advancing member, a pair of contacts, an interrupter for intermittently opening and closing said contacts, and means under the control of said traversing apparatus for actuating said interrupter during the interim between passing from a selected one of said members to a subsequently selected member.
  5. In a telegraph transmitting system, means to generate various pluralities of signal interruptions each representing a character comprising a rotatable member, a plurality of elements each assigned to a character and peripherally distributed about said rotatable member, means conditioned by perforations in a control form to present selectively one of said plurality of members into the path of said rotatable member, and means actuated by said rotatable member for initiating the performance of said conditioned means to respond to subsequent perforations in said form.
  6. The combination set forth in claim 5 in which said means is conditioned by a plurality of form sensing members, an electromagnet for cyclically restoring said form sensing members to permit the advancement of the form, and a delayed response relay for energizing said electromagnet to withdraw said form sensing members after the lapse of a predetermined time interval.
  7. In a transmitting mechanism, a device for generating line pulsations comprising a rotatable member, a selecting apparatus for arresting said member in various angular positions, a control form sensing apparatus comprising means for ascertaining control form markings and means for feeding a form to present subsequent markings to said ascertaining means, sensing apparatus initiating means under the supervision of said rotatable member, and means for communicating a setting from said ascertaining means to said selecting apparatus for each operation of said form feeding means.
  8. In a telegraph transmitting mechanism, a transmitter shaft including means for generating signal interruptions corresponding to the angular rotation of said shaft, a tape sensing mechanism
- 5 10 15 20 25 30 35 40 45 50 55 60 65 70 75

comprising a set of tape sensors and a tape feed mechanism, a power shaft including a frictional coupling for communicating the actuating power to said tape sensing mechanism, means under the control of said tape sensing mechanism for determining the angular position of arresting said transmitter shaft, and means responsive to an arrest of said transmitter shaft for establishing the coupling between said tape sensing mechanism and said power shaft.

9. The combination set forth in claim 8 in which said transmitter shaft and said power shaft are driven from a common source of power.

10. In a selector mechanism, a plurality of circular discs in concentric alignment having peripherally thereof notch and lug selecting attributes, a plurality of selectable rods spaced and aligned around said alignment of discs, spring means for urging said rods into engagement with the periphery of said discs, a frictionally driven shaft concentric of said discs, a seeker arm carried by said shaft having an extreme member which traverses the proximity of said rods and is actuatable by a conditioned one of them, and a mean member moved by said extreme member having a contact controlling portion disposed in alignment with the axial center of said shaft.

11. The combination set forth in claim 10 in which said seeker arm is provided with duplex extreme and mean elements, and in which said plurality of selectable rods are confined to occupy substantially one-half of the periphery of said discs.

12. In a device for converting permutation code signals into step-by-step signals, the combination including a rotatable shaft, frictional driving means for imparting rotation to said shaft, an interrupter carried by said shaft for generating line pulsations, means for controlling the angular rotation of said shaft comprising a set of disc selectors, a plurality of selectable pins peripherally distributed about said set of selectors and movable during selection into an arresting zone, a tape feed mechanism for advancing a control form to supervise the positioning of said disc selectors, a switch controlling stop member carried by said shaft and blocked by said pins when moved into said arresting zone, and means carried by said stop member for controlling said tape feed mechanism.

13. In a telegraph transmitting mechanism, means for generating alternate current conditions for signalling over a line including a rotary arm, a permutation selecting device, means under the control of said permutation selecting device for arresting said rotary arm in various angular positions, and means under the control of said arm for determining the instant of restarting said arm into rotation.

14. A telegraph transmitter comprising a switch for generating current interruptions, a rotary member for actuating said switch, a plurality of selectable elements, and means for individually conditioning said selectable elements to arrest said rotary member predeterminedly in its cycle of rotation, said conditioning means comprising a set of discs having sets of aligned openings, and means for setting said discs including a set of shafts one associated with each of said discs and extending through one of said sets of alignment of openings, and cam means carried by said shaft secured in transverse alignment each with its associated one of said discs.

15. In a selector mechanism, a set of parallelly arranged selector members having transversely aligned openings therethrough, and means for setting said members in accordance with the permutation components of a code comprising a device extending through each alignment of openings and associated with one of said members, and a projection carried by each of said devices for communicating a setting movement from said device to its said associated member.

16. In a code translating apparatus, a power driven instrumentality, a record reader including an intermittent feeding device driven by said power instrumentality, a selective translator including a rotary switch controller driven by said instrumentality, and a mechanical linkage under the supervision of said rotary switch controller for permitting the engagement of said power driven instrumentality and said feeding device.

17. In combination, a selector mechanism including a set of code members having various distributions of notches and lugs for establishing individual selective clearances, tape controlled means for positioning said code members, and all-mechanical means responsive to each selective placement of said members for advancing a tape through which said selector mechanism is controlled.

18. In combination, a plurality of selectively conditionable devices arranged in a circular path, a rotary seeker driven to traverse said path and responsive specially to any of said devices in selected condition, means for generating signal interruptions during the transitory period of said seeker moving from one conditioned one of said devices to another, a record sensing mechanism responsive to perforations in a tape for selectively conditioning said devices in accordance with related perforation signals, and means under the control of each special response of said rotary seeker for operating said record sensing mechanism.

19. The combination set forth in claim 18 in which said selectively conditionable devices are arranged in a semi-circular path and in which said rotary seeker is a duplex member having identical opposite portions each effective during one-half of a revolution.

20. In a mechanical permutation selector mechanism, a set of rotationally shiftable code elements having peripherally thereof selection clearances and obstructions, a plurality of selectable elements surrounding said discs, means for individually selecting said elements by permutative presentation of said selection clearances under individual disposition of said discs, and mechanical means for shifting said discs comprising rock shafts extending through openings in said discs and longitudinally of their axis of rotation, signal responsive means for imparting movement to said shafts, and elements individual to each of said shafts having articulation with corresponding ones of said discs.

21. In a telegraph transmitter, a rotatable signal controlling member, selectively conditionable means for arresting said member variously including a perforated tape sensing mechanism, and apparatus including said rotatable member and a selection responsive means for regulating the progress of tape in said sensing mechanism.
